BY Farthes & Co. ATTY'S.

UNITED STATES PATENT OFFICE.

CARL SCHEID, OF HARRISON, NEW JERSEY, ASSIGNOR TO THE DRAPER COMPANY, OF PORTLAND, MAINE.

SPINDLE.

SPECIFICATION forming part of Letters Patent No. 590,378, dated September 21, 1897.

Application filed April 19, 1897. Serial No. 632,742. (No model.)

To all whom it may concern:

Be it known that I, CARL SCHEID, a citizen of the United States, residing in Harrison, county of Hudson, and State of New Jersey, 5 have invented certain new and useful Improvements in Spindles; and I do hereby declare the following to be a full, clear, and exact description of the invention, such as will enable others skilled in the art to which it 10 appertains to make and use the same, reference being had to the accompanying drawings, and to letters of reference marked thereon, which form a part of this specification.

The object of my present invention is to 15 provide a spindle-supporting tube with means for adjustably mounting said spindle on the spindle-rail and at the same time permitting said spindle to be set at an oblique angle to the said rail.

20 The invention consists in the details of construction, substantially as will be hereinafter more fully described, and finally embodied in the clauses of the claim.

In the accompanying drawings, Figure 1 is 25 a front elevation of a portion of the spindle-rail, in which is mounted a spinning-spindle provided with my improvements; and Fig. 2, a sectional view on the line *x x* of Fig. 1.

In said drawings, *a* represents the spindle- 30 rail, provided with the vertical bore or opening *a'*, in which is loosely mounted the tube *b*, having the annular flange *c*, resting on the top of the spindle-rail, and containing step- and-bolster bearing for the spindle *d*. The 35 latter is provided with the sleeve *e* and whirl *f*, through which motion is imparted to the said spindle.

On the lower portion of the tube *b* is adjustably arranged a ring or collar *i*, by means 40 of the set-screw *i'*, and bears against the spiral spring *m*, surrounding said tube and bearing with its upper portion against the under side of the rail *a* or against an intermediate

metallic washer *n*, all as clearly shown and of the usual and well-known construction.

45 The annular flange *c* of the tube *b* is penetrated by a series of set-screws *g*, arranged vertically, and preferably in a triangle, and engaging with their lower ends recesses or sockets *g'*, arranged in the top portion of the 50 spindle-rail.

The elasticity of the spindle *d* is regulated, by means of the washer *i*, in the usual manner, while the relative position between the spindle *d* and the rail *a* is regulated by means 55 of the set-screws *g*—that is to say, the spindle *d* can easily be set at an oblique angle to the spindle-rail by simply operating one or more of said set-screws, the latter raising or lifting the corresponding side or portion of the 60 annular flange *c*, as will be manifest.

Having thus described my invention, what I claim as new, and desire to secure by Letters Patent, is—

65 The combination with the spindle-rail, provided with a vertical bore or opening, of a tube penetrating said opening and loosely mounted on the spindle-rail, and provided with an annular flange above said rail, a ring or washer adjustably arranged on the lower 70 portion of said tube, a spiral spring surrounding said tube and intermediately arranged between the spindle-rail and said washer, a series of set-screws penetrating the annular flange of said tube and bearing on the spindle-rail, and a whirl-driven spindle in said tube, all said parts, substantially as and for 75 the purposes described.

In testimony that I claim the foregoing I have hereunto set my hand this 5th day of April, 1897.

CARL SCHEID.

Witnesses:

ADAM SCHEID,
Wm. D. BELL.
